(57) **CLAIM**

The ornamental design for a desktop laser cutter, as shown and described.

DESCRIPTION

The present application is an application for reissue of U.S. Pat. No. D. 850,528, issued on Jun. 4, 2019, which corresponds to U.S. patent application Ser. No. 29/586,721, and is a divisional application of U.S. Pat. No. D. 827,705, issued on Sep. 4, 2018, which corresponds to U.S. patent application Ser. No. 29/540,496, the entire contents of each of which are incorporated herein by reference.

FIG. 1 is a top-left perspective view showing an embodiment of the desktop laser cutter;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and

FIG. 7 is a bottom plan view thereof.

FIG. 8 is a top-left perspective view showing a second embodiment of the combined desktop laser cutter and filter;

FIG. 9 is a right side elevational view thereof;

FIG. 10 is a left side elevational view thereof;

FIG. 11 is a front elevational view thereof;

FIG. 12 is a rear elevational view thereof;

FIG. 13 is a top plan view thereof; and,

FIG. 14 is a bottom plan view thereof.

The broken lines in the drawings illustrate environment and portions of the desktop laser cutter, which form no part of the claimed design.

The oblique line shading in the perspective views and the top plan views illustrate transparent surfaces.

1 Claim, 14 Drawing Sheets

Matter enclosed in heavy brackets [ ] appears in the original patent but forms no part of this reissue; matter printed in italics indicates the additions made by reissue.
